UNITED STATES PATENT OFFICE.

JOHN B. YATES WARNER, OF SCOTTSVILLE, NEW YORK.

PORTABLE ROOF.

1,187,210.

Specification of Letters Patent. Patented June 13, 1916.

Application filed December 17, 1915. Serial No. 67,367.

To all whom it may concern:

Be it known that I, JOHN B. YATES WARNER, a citizen of the United States, and a resident of Scottsville, in the county of 5 Monroe and State of New York, have invented a new and Improved Portable Roof, of which the following is a full, clear, and exact description.

My invention, while capable of various 10 uses as a roof or shelter, is more particularly designed, in its illustrated form, for providing a roof for stacks of hay, straw, or the like.

An object of the invention is to provide a 15 structure composed of elements that may be assembled in small compass in knocked down form for storage or shipping and which may be readily erected in any desired length according to the size of the stack or other material or location to be covered or sheltered.

A further object of the invention is to provide supporting and anchoring means for the roof of the structure, which may be readily entered in the stack or in the ground 20 and will afford substantial support for the roof.

Other objects and advantages of my improved structure will appear from the description following.

Reference is to be had to the accompanying drawings forming a part of this specification in which similar reference characters indicate corresponding parts in all the views.

Figure 1 is a longitudinal vertical section of a portable structure embodying my invention, showing the same in use on a stack; Fig. 2 is a transverse vertical section on the line 2—2, Fig. 1; Fig. 3 is a fragmentary 35 perspective view showing means for connecting an anchor to the roof plates; Fig. 4 is a detail transverse vertical section on an enlarged scale, showing the manner of connecting the roof plates or sections with the 40 ridge pole of the structure; and Fig. 5 is an enlarged cross section of the ridge pole and a coupling employed to flexibly support the same on my improved props, a fragment of one of which is shown in side elevation.

In constructing a practical embodiment 50 of my invention in accordance with the illustrated example, two sheets 10 are provided of corrugated iron, which may be disposed as a lean-to or as a peak-roof. In case of a 55 hay stack, or the like, the sheets will be disposed to form a peak-roof as shown. The

upper ends of the sheets are adapted to be detachably engaged with a ridge pole 11, which is supported by props 12. The lower ends of the roof sheets are secured to 60 anchors 13.

On each roof sheet, near the ends, cross bars 14, 15 are riveted, or otherwise fastened, thereto to reduce the flexibility of the sheets, and to provide means for the securing of the 65 sheets in position as hereinafter explained. The respective cross bars of a sheet, it will be observed, are at different distances from the ends, the purpose of which is to permit of the upper ends of the sheets at one side 70 of the peak-roof extending over the adjacent upper ends of the sheet at the opposite side of the roof, as clearly shown in Fig. 2.

On the ridge pole 11, fastening means is provided to detachably engage the upper 75 ends of the roof sheets. Preferably, the fastening means consists of hooks 16, formed with loops 17 loosely embracing the ridge pole and formed with hooks 18 at their lower ends to engage the adjacent cross bars 80 14, 15 of the sheets. The roof sheets will thus be firmly sustained on the ridge pole but will be free to be moved to vary their angular positions.

The ridge pole 11 is formed of short sections, preferably of pipe, the sections being connected by couplings 19 and the fastening members 16 are strung on each section. In practice, the corrugated roof sheets are approximately 25 inches wide by 10 feet long 85 and the ridge pole sections may be 2 or 4 feet, or alternately 2 and 4 feet. The described form and arrangement permits of the structure being extended to any desired length and also, permits of its being gradually shortened by the removal of the roofing sections as the stack becomes smaller.

Each prop 12, for sustaining the ridge pole, includes a standard 20 preferably consisting of a length of pipe, and the lower portion of the prop is in the form of an anchor, designated generally by the numeral 21. The prop is received at its upper end in a three-way or four-way coupling 22, which embraces the ridge pole 11 sufficiently 100 loose to permit of the pole changing in its angular position relatively to the props in case the stack should settle. The standards 20 are connected with the anchors 21 by four-way couplings 23, there being also preferably employed, a nut 24 on the anchor which takes into the said coupling. If de-

- sired, the standard 20 and the coupling 22, at the top thereof, may be taken off and the ridge pole passed directly through the four-way coupling 23. Each anchor 21 is formed 5 with a screw or spiral 25, intermediate the ends thereof, so as to terminate at its lower end a substantial distance from the lower end of the anchor, whereby to provide an elongated pointed shank 26 below the spiral.
- 10 With the described form of prop, the straight shank terminal 26 is entered in the hay stack or other material and the anchor is then turned to screw the spiral 25 into the material, the straight front terminal serving 15 to guide the spiral straight into the material. The construction insures the firm securing of the prop in position so that a substantial body of hay would have to be lifted by the wind to displace the prop.
- 20 The anchors 13 for the lower ends of the roof sheets 10 are, in general, similar to the anchor members 21 of the props 12, each anchor being formed with a spiral 27 sufficiently distant from the pointed lower end 25 of the anchor to provide a straight shank member 28 corresponding with the member 26 of the anchor 21. In connection with each anchor 13 I employ means to engage and tie two adjacent roof sheets near the lower ends. Said means includes a double hook 30, the hook members 30 of which are adapted to engage beneath an adjacent cross bar 14 or 15 on the respective roof sheets. The
- 30

hooks 29 are suitably secured to eyes 32 of the respective anchors 13, a piece of wire or 35 cord 31 serving for the purpose.

Having thus described my invention I claim as new and desire to secure by Letters Patent:

A structure of the class described including separate roof sheets having cross pieces secured thereto near each end, the respective cross pieces of a sheet being at different distances from the respective ends, a ridge pole made in detachable sections, hook members 40 loose on the ridge pole to turn thereon, and adapted to detachably engage the adjacent cross bars on the roof sheets, props for the ridge pole, said props having self-anchoring lower portions, couplings receiving the upper ends of the props and loosely engaging the ridge pole to permit relative movement thereof to alter their angular relation, anchors for the lower ends of the roof sheets, fastening members adapted to detachably engage the cross bars of two adjacent roof sheets, and means to secure said fastening members to the adjacent anchors. 45

50

In testimony whereof I have signed my name to this specification in the presence of 60 two subscribing witnesses.

JOHN B. YATES WARNER.
